UNITED STATES PATENT OFFICE

WILLIAM C. KINNON, OF DENVER, COLORADO

SINTERING MACHINE

Application filed July 12, 1930. Serial No. 467,404.

This invention relates to a sintering machine, more particularly of the type for preparing ore concentrates, such as sulphides, for smelting operations, but adaptable for use in any sintering process.

The principal object of the invention is to provide a sintering machine which will handle a continuous feed and constantly deliver completely sintered material.

Another object of the invention is to so construct the machine that the fines and dust which pass through the grates will be collected and continuously advanced to a discharge point by the same motion employed for advancing the sintered material.

Another object of the invention is to employ an intermittent advancing motion so that the sinter cake will remain at rest for continuous periods of short intervals. Thus, insuring a more complete oxidation and sintering of the advancing bed.

Still another object of the invention is to provide a machine of this character which will continuously advance a bed of sinter cake without the use of conveyors, scrapers, or other means which might become caked, fouled, or clogged.

A further object of the invention is to so construct the machine that the thickness of the bed and the speed of advancement of the sinter cake may be minutely adjusted to the characteristics of raw material, and other variable conditions.

A still further object of the invention is to provide an ignition device which will uniformly ignite the traveling bed throughout its entire width so that the material will rapidly and uniformly oxidize and to so construct the igniting portion of the device that it may be vertically adjusted to obtain the desired flame and to suit the thickness of the bed or cake.

Other objects and advantages reside in the detail construction of the invention, which is designed for simplicity, economy, and efficiency. These will become more apparent from the following description.

In the following detailed description of the invention reference is had to the accompanying drawings which form a part hereof.

Like numerals refer to like parts in all views of the drawings and throughout the description.

In the drawings:

Fig. 1 is a side elevation of a preferred form of the invention partially broken away to illustrate the interior construction.

Fig. 2 is a vertical cross section therethrough taken on the line 2—2, Fig. 1.

Fig. 3 is an enlarged, horizontal cross section through the igniter taken on the line 3—3, Fig. 1.

Fig. 4 is a fragmentary detail perspective view of the grate bars employed in the invention.

The invention comprises an open topped box 10 of sheet metal. The box 10 is stiffened about its open top by means of a channel-iron frame 11. Adjacent the discharge extremity, the bottom of the box 10 is provided with a collecting chamber 15 from which the contents may be discharged through a gate 16.

A series of parallel, spaced-apart, horizontal, grate bars 12 is placed within the box 10. The grate bars 12 may be supported in the box 10 in any desired manner such as upon an angle shelf 13 at each side thereof. The grate bars 12 are preferably designed as illustrated in Fig. 4 with relatively broad tops and relatively narrow bottoms and with spacer lugs 14 cast upon their extremities to properly align and separate them in the series.

Each grate bar 12 is positioned slightly lower than its preceding bar so that the entire series forms a stepped, inclined plane within the box 10 for the support of the material bed or sinter cake. The portion of the box 10 above the grate bars 12 is lined with heat resisting material as shown at 44.

The entire box 10 is flexibly suspended from concrete piers 17 or other suitable supports. As illustrated channel iron caps 18 are placed upon the piers 17 over a notch formed therein. Straps 19 of flexible material, such as webbing, metallic leaves, or the like, depend from angle clips 20 upon the channel irons 18. The lower extremities of the strips 19 are attached to angle brackets 21 secured to

upon the box 10. Thus the box 10 is free to swing longitudinally.

Longitudinal movement is imparted to the box 10 by means of a suitable vibrating mechanism 22 which is connected to the box 10 by a connecting beam 23. The vibrating mechanism, per se, forms no part of the present invention, and might be any of the usual types of mechanical or electrical vibrators employed in the ore dressing art for vibrating concentrating tables, jigs, screens, etc. It should be of the type known as the "quick return" so that it will move the box 10 relatively slowly toward the right or discharge end and then jerk or snap it back toward the feed end.

A constant down draft of air is maintained through the intervening spaces between the grate bars 12 by means of a suitable exhaust fan 24, which is connected through a flexible coupling 25 to a boot 26 which opens to the box 10 below the grate bars 12. The fumes are discharged from the exhaust fan 24 through a suitable stack 45.

Material is fed to the machine from any suitable continuous feeder through a chute 27 which discharges into a feed hopper 28 immediately above the grate bars at their highest point. It can be readily seen that this material owing to the constant longitudinal vibration of the box 10 will uniformly travel across the series of grate bars and discharge from a discharge outlet 29 at the opposite extremity of the machine.

The material is immediately ignited after reaching the machine by means of an igniter 30. The igniter 30 is supported from threaded rods 31 extending from any suitable supporting frame 32. The rods 31 are provided with nuts 33, one of which may be rotated by means of a hand wheel 34. The two nuts 33 are caused to rotate in unison by a connecting chain 35. Thus, when the hand wheel 34 is rotated the igniter is raised or lowered. It is preferred to carry the feed hopper from the igniter 30 so that it will raise or lower therewith.

The igniter is preferably designed to burn fuel oil but is adaptable to other fuels. In the installation illustrated the fuel oil is fed from a suitable reservoir 36 from which it feeds through a flexible conduit 37 and a burner valve 38 to a discharge nozzle 47. The nozzle 47 is positioned within a burner 46 to which air is supplied by a blower 39. The interior construction of the igniter 30 is shown more in detail in Fig. 3. The blaze from the burner 46 is projected into a flame compartment 40 into which a series of diagonally-placed, flame baffles 41 project. Each of the baffles 41 serve to turn or direct a portion of the flame side-ward and downward toward a discharge orifice 42, which extends throughout the entire length of the bottom of the igniter 30 and the entire width of the

box 10. The interior of the igniter is protected by a suitable refractory lining 43 of fire clay or similar material.

Operation

The vibrator 22, the exhaust fan 24, and the igniter 30 are started. The ore or other material to be sintered is fed to the feed hopper 28. The operator adjusts the hand wheel 34 to bring the feed hopper to the desired height to spread the thickness of bed desired. The longitudinal motion of the box 10 causes the fed material to travel away from the feed hopper 28 under the flame from the igniter 30, which completely ignites the material at this point. The material continues to advance and the combustion is maintained therein by the down blast of air through the bed and between the grates. As the box 10 swings toward the discharge end the bed will be advanced and will remain in the advanced position while the box 10 is jerked back to the starting position. It will again move forward on the next stroke of the vibrator 22. Thus the bed continuously advances by a series of intermittent movements the length and intensity of which may be controlled by adjustment of the vibrator 22. The combustion or oxidation will be completed and the sinter cake formed before the bed reaches the discharge opening 29, from which the sinter cake will be constantly discharged into any suitable receiving apparatus.

The exceedingly fine material and dust which falls or is drawn between the grates by the draft, collects on the bottom of the box 10 and is continuously collected and advanced toward the dust hopper 15 by the reciprocatory action of the box 10. This dust may be collected at intervals by opening the gate 16 and returned to the feed chute for retreatment.

It is desired to call particular attention to the novel arrangement and action of grate bars 12. The bars 12, by being stepped slightly downward toward the discharge, act analogously to a ratchet upon the bed and sinter cake. That is, they present projecting edges which prevent movement of the bed toward the feed end and which serve to push or impel the bed toward the discharge end. The wedge shape of the bars 12 serves to prevent material from packing and clogging between the bars.

While the invention has been described as particularly applied to a sintering machine, it is desired to be understood that it is, of course, not limited to this use but will find many other applications, such as roasting ores or heating ores for the recovery of mercury after amalgamation processes, etc.

While a specific form of the improvement has been described and illustrated herein, it is desired to be understood that the same may

be varied, within the scope of the appended claims, without departing from the spirit of the invention.

Having thus described the invention, what is claimed and desired secured by Letters Patent is:—

1. A sintering machine comprising: a supporting structure; a relatively long box; means for flexibly suspending said box from said supporting structure so that it may swing in a longitudinal direction; a vibrating mechanism operatively connected to said box so as to reciprocate it in a longitudinal direction; a series of grate bars positioned in said box; means for feeding the material to be sintered onto said grate bars adjacent one extremity of said box, there being a discharge opening for said material adjacent the other extremity of said box; and means for igniting said material adjacent said feeding means.

2. A sintering machine comprising; a supporting structure; a relatively long box; means for flexibly suspending said box from said supporting structure so that it may swing in a longitudinal direction; a vibrating mechanism operatively connected to said box so as to reciprocate it in a longitudinal direction; a series of grate bars positioned in said box; means for feeding the material to be sintered onto said grate bars adjacent one extremity of said box, there being a discharge opening for said material adjacent the other extremity of said box; means for igniting said material adjacent said feeding means; and an exhaust fan opening to said box below said grate bars so as to draw air downwardly through the material thereon and maintain combustion therein.

3. A sintering machine comprising: a supporting structure; a relatively long box; means for flexibly suspending said box from said supporting structure so that it may swing in a longitudinal direction; a vibrating mechanism operatively connected to said box so as to reciprocate it in a longitudinal direction; a series of grate bars positioned in said box; means for feeding the material to be sintered onto said grate bars adjacent one extremity of said box, there being a discharge opening for said material adjacent the other extremity of said box; means for igniting said material adjacent said feeding means; a receiving chamber in the bottom of said box adjacent the discharge extremity thereof; and means for discharging material from said receiving chamber.

4. In a sintering machine arranged to impart a traveling motion to a bed of material to be sintered, means for igniting said material adjacent its point of entrance to said bed comprising: an igniter positioned laterally across said bed; a supporting structure; adjustable mounting means between said igniter and said structure so that the height of the former relative to said bed can be adjusted;

and a feed hopper carried by said igniter so that vertical adjustment of the latter will adjust said hopper vertically to determine the thickness of said bed.

5. An igniter for sintering machines comprising: a relatively long housing adapted to extend laterally across a bed of material to be ignited; a burner positioned to project a flame longitudinally into said housing; means for deflecting said flame through a longitudinal opening in the bottom of said housing toward said bed, said means comprising: a series of diagonally placed baffles arranged to project into said flame at spaced apart positions throughout its length.

6. A sintering machine comprising: a sheet metal box; grate supporting members extending along the sides of said box; a series of laterally spaced-apart grate bars carried by said supporting members adjacent the open top of said box, each of said bars being positioned slightly lower than its preceding bar so that said series will form a stepped incline; supporting means for said box adapted to allow longitudinal movement thereof; means for imparting opposite longitudinal movements such that material on said grate bars will be intermittently advanced down said stepped incline.

7. A sintering machine comprising: an open-topped, sheet metal box; grate supporting members extending along the sides of said box; a series of laterally-positioned, spaced-apart, grate bars carried by said supporting members adjacent the open top of said box, each of said bars being positioned slightly lower than its preceding bar so that said series will form a stepped incline; supporting means for said box adapted to allow longitudinal movement thereof; means for imparting a longitudinal movement to said box so that material on said grate bars will be intermittently advanced down said stepped incline; and a feed hopper arranged to feed material onto said grate bars adjacent the highest point of said incline; and means for raising or lowering said feed hopper so as to determine the thickness of a bed of material on said bars.

8. A sintering machine comprising: an open-topped, sheet metal box; grate supporting members extending along the sides of said box; a series of laterally-positioned, spaced-apart, grate bars carried by said supporting members adjacent the open top of said box, each of said bars being positioned slightly lower than its preceding bar so that said series will form a stepped incline; supporting means for said box adapted to allow longitudinal movement thereof; means for imparting a longitudinal movement to said box so that material on said grate bars will be intermittently advanced down said stepped incline; a feed hopper arranged to feed material onto said grate bars adjacent the high-

est point of said incline; means for raising or lowering said feed hopper so as to determine the thickness of a bed of material on said bars; and an igniting device extending laterally across said box above said bars so as to project a flame upon the material leaving said feed hopper; and means for exhausting the air from said box below said grate bars so as to maintain combustion in said ignited material.

10. A sintering machine comprising: a longitudinal series of laterally positioned, spaced-apart grate bars, each of said bars being positioned slightly lower than its preceding bar so that said series will form a stepped incline; supporting means for said series adapted to allow longitudinal movement thereof; means for imparting opposite longitudinal movements such that material on said grate bars will be intermittently advanced down said stepped incline.

In testimony whereof, I affix my signature.

WILLIAM C. KINNON.
